[57] CLAIM

The ornamental design for a weed cutting attachment for a riding mower, as shown and described.

DESCRIPTION

FIG. 1 is a perspective view of the weed cutting attachment for a riding mower embodying the design of the present invention;

FIG. 2 is a front elevational view thereof;

FIG. 3 is a front elevational view thereof;

FIG. 4 is a side elevational view thereof;

FIG. 5 is a side elevational view thereof;

FIG. 6 is a top plan view thereof; and,

FIG. 7 is a bottom plan view thereof.

FIG.1

FIG. 2

FIG. 3

FIG.4

FIG.5

FIG. 6

FIG. 7
